United States Patent Office.

REUBEN RAMSDELL, OF RINDGE, NEW HAMPSHIRE.

Letters Patent No. 79,858, dated July 14, 1868.

IMPROVEMENT IN MACHINES FOR MAKING WOODEN BOXES.

The Schedule referred to in these Letters Patent and making part of the same.

TO ALL WHOM IT MAY CONCERN:

Be it known that I, REUBEN RAMSDELL, of Rindge, in the county of Cheshire, and State of New Hampshire, have invented an Improvement in the Manufacture of Round and Oval Wooden Boxes; and I do hereby declare that the following, taken in connection with the drawings which accompany and form part of this specification, is a description of my invention sufficient to enable those skilled in the art to practise it.

In the manufacture of fig and other similar wooden boxes, using a block or former to determine the size of each box, and to facilitate the bending and nailing, it is customary to employ an iron or metal-surfaced elliptical block, having extending from its outer and upper surface a series of metal pins or other projections, which hold the wood above the surface of the block, so that, in driving the nails, to make the body or cylindrical part of the box, the points of the nails pass freely through the wood, and then, striking the surface of the block, are deflected or turned over, so that they can readily be clinched.

This method is defective, in that the points of the nails deflect in any direction, whereas it is necessary, in order to make the box tight and its interior smooth, that they should turn and be clinched crosswise of the grain of the wood, instead of following the curved surface thereof.

The primary object of my invention is to so construct the former-block that the nails shall all deflect in a direction across the grain, or towards either end of the box; and for this purpose I make the metal or metal-surfaced former-block with a series of parallel grooves in its upper surface, and running from head to head of the block, the wood being wound around and directly against the block, and the point of each nail entering one of the grooves, and being deflected by the sides thereof, so that it turns towards one or the opposite end of the block.

It is this construction which mainly constitutes my invention, and the drawings represent a machine embodying the same.

A shows a side elevation,

B a front elevation, and

C a plan thereof.

a denotes a bed, upon which is erected an upright or standard, *b*, at the upper end of which is the former or anvil-block *c*, made stationary with respect to the standard.

This anvil-block is made of metal, or covered with metal, and across its upper surface are the parallel scores or grooves *d*, each made deep enough to allow the point of the nail to turn and bend over within it, the particular groove met by the nail-point giving the direction to the nail, or causing it to bend over and clinch against the wood in a direction towards one or the other of the heads of the block.

In connection with this block, I use an adjustable-jaw block, *e*, for gripping the end of the piece from which the body or cylindrical part of the box is made, and for determining the size of the box. This jaw is hung and turns on a pin, *f*, and opens from and closes against the block *a*, on each side of the pin *f*, as will be seen at B. The jaw-piece *g* is for gripping the end of the stock, and holding it securely, (against a spring or yielding plate, *h*), while the band of wood is drawn tightly around both blocks, *c* and *e*, and lapped, as seen at B, the nails being then driven through the lapped piece and the piece beneath, as will be readily understood. The long jaw *i* is arrested in its downward movement by the head of an adjusting-screw, *k*, screwed into the block *a*, the piece *i* having a recess, *l*, through which the screw is entered, and into which the head projects, and a seat, *m*, which brings up against the head of the screw, the shank of the screw passing loosely through the piece *i*, above this seat.

It will be obvious that, by turning up the screw more or less, the extent of downward movement of the jaw *i* may be diminished or increased, and that the size given to the box will be thereby varied.

The movement of the jaws is effected by a treadle, *p*, connected to the jaw *i* by connecting-rods *q*, and the box is released, and the jaws thrown back to their normal position, by a spring, *r*. When so released, the body is removed, and the head driven into one of its open ends. The cover of the box may be similarly made, as will be readily understood.

By the mechanism so constructed and arranged, the operation of making cylindrical wooden boxes is simplified and expedited, and a better box can be made than by following the old method.

I claim, in combination with the former-block or its equivalent, the groove or grooves *d*, for turning the nail-points, substantially as set forth.

Also, in combination with the block *c*, the jaw-block *e*, with its clamping or gripping-jaw *g* and the spring *h*, substantially as set forth.

Also, combining with the jaw *e* and the block *c* the adjusting-screw *k*, substantially as and for the purpose set forth.

REUBEN RAMSDELL.
